UNITED STATES PATENT OFFICE.

WALTER SAMUEL STELJES, OF LONDON, ENGLAND.

STEP-BY-STEP PRINTING-TELEGRAPH.

SPECIFICATION forming part of Letters Patent No. 624,561, dated May 9, 1899.

Application filed February 16, 1899. Serial No. 705,609. (No model.)

To all whom it may concern:

Be it known that I, WALTER SAMUEL STELJES, engineer, a subject of the Queen of Great Britain, residing at Mountview, Mount Pleasant road, South Tottenham, London, in the county of Middlesex, England, have invented certain new and useful Improvements in Step-by-Step Printing-Telegraphs, of which the following is a specification.

- 10 In step-by-step printing-telegraphs it has before been proposed to drive both the type-wheel and an axis for effecting the printing and feeding forward of the paper by weights or springs. It has also been proposed to use 15 one magnet having two armatures, one for operating the escapement used for controlling the turning of the type-wheel and the other for operating the escapement used for controlling the turning of the printing-axis.
- 20 My improvements relate to an improved construction and arrangement of the electromagnet and its armatures to allow of its being operated by very light reverse currents from a magneto-machine and also to improved 25 means for shifting the type-wheels along their axis to bring one type-wheel into acting position when the other is moved away from that position.

My improvements are shown in the drawings annexed.

Figure 1 is a face view of the machine. Fig. 2 is a side elevation of the electromagnet and the two axes whose revolution it controls, the one axis carrying the type-wheels 35 and the other controlling the printing and moving forward of the paper. Fig. 3 is a partial plan view showing these parts. Fig. 4 is a side view of the type-wheel axis when this axis is in the position shown in Fig. 3. 40 Fig. 5 is a similar view with some of the parts in a different position. Fig. 6 is an elevation of the type-wheel-escapement armature, looking at the front face or that adjacent to the magnet. Fig. 7 is an end view of the same; 45 Fig. 8, an elevation of the rear face of the same.

A and B are two trains of wheels, each driven by a spring or weight. The train of wheels A drives the type-wheel axis C, and the train of wheels B drives the axis D, which 50 controls the printing and feeding forward of the paper.

C^x are type-wheels.

E are the core-pieces of the electromagnet. E' are arms extending sidewise from these cores in parallel planes at a distance apart 55 from one another.

G is an armature in front of the ends of the arms E' and fixed centrally upon a vertical axis G', one end of the armature being opposite to the end of one arm and the other end of the armature opposite to the end of the other arm. The armature is also divided across the middle and a piece of brass y or other non-magnetic substance interposed between the two parts, thus interrupting the magnetic continuity of the armature at or about midway of its length.

H is an armature carried by a lever H' below the lower ends of the cores E. The upper ends of the cores E are attached to one 70 end of a permanent magnet F. The other end of the permanent magnet comes at the back of the armature G and very effectively magnetizes the two parts of this armature to one polarity, while the electromagnet-cores E are 75 magnetized to the opposite polarity.

By mounting the armature G upon a central axis in the above way, with one of its ends opposite to one arm E' and its other end opposite to the other arm, the two armatures 80 can, as shown, be kept at a considerable distance apart from one another, so that the magnetic field acting upon the one armature is well away from the magnetic field acting upon the other armature, and the armature H is 85 but little, if at all, affected by the magnetism of the permanent magnet F, whereas heretofore when one polarized magnet has been used for operating upon two armatures the side-wise extensions or arms of the magnet-cores 90 have been made to face toward one another, and one end of a polarized rocking armature has been arranged to oscillate to and fro between them. This armature and the armature in front of the ends of the magnet-cores 95 have thus been brought into close proximity.

By dividing the armature G across the middle its movements are rendered perfectly steady and uniform and it responds readily to every alternation of current, and although 100 a slightly-stronger current may be required by reason of the extent to which the magnetic circuit of the electromagnet is completed through the armature being somewhat re-

duced, yet this tends to render the movements of the armature steady, and also when one end of the armature is attracted to one arm E' the polarity of the other end of the 5 armature remains entirely unaltered.

When alternate currents are passed in regular succession through the coils of the electromagnet, the polarity of one magnet-core E is intensified and the other reversed at each reversal of current. One end of the armature G is thus attracted to the end of one arm E' and the other end of the armature is repelled from the other arm E', and the armature is thus rocked to and fro at the same time the armature H is attracted to the cores E and remains held up so long as alternate currents are passing. When the currents cease to pass, the armature H drops away from the magnet-cores.

20 G² is a tooth or pallet carried by an arm which extends from the armature-axis G'. As the armature is rocked this pallet engages first with the teeth of one escapement-wheel I, which is fast on the type-wheel axis C, and 25 then with the teeth of another escapement-wheel I, which is alongside it, each movement allowing the escapement-wheels to make a partial turn, and so the type-wheel axis C is allowed to revolve with a step-by-step movement so long as alternate currents are passing through the coils of the electromagnet.

The lever H', which carries the armature H, also carries two pallets H² H³, against one or other of which a blade projecting from an 30 arm D', which is fast on the axis D, rests. The blade rests against the pallet H² so long as the armature remains attracted to the magnet-cores E; but when currents cease to pass and the armature drops the pallet H² is moved 35 away from in front of the blade and the arm D' makes approximately a complete revolution. The blade upon it then comes against the pallet H³ and is arrested by this pallet and remains arrested by it until the armature H is 40 again attracted. This movement carries the pallet H³ out of the way of the blade on the arm D', and the blade comes against the pallet H² and is arrested by it until the armature again drops. Whenever the axis D is allowed 45 to make a complete turn in the way above described, an eccentric D² upon it lifts the lever-arm J, which turns on an axis at J', and then again lowers this arm. The lever-arm carries a roller J², over which passes the strip of 50 paper X to be printed on. When the lever-arm is raised, it brings the paper against whichever letter on the under side of the type-wheel is opposite to it and causes this type to make its impression upon the paper. When 55 the lever again descends, a pawl J^X, acting upon a ratchet-wheel fast with the roller J², gives a partial turn to this roller and so feeds forward the paper ready for the next impression.

60 65 The rocking movement of the armature G is limited by adjustable stops G^X, and the

rocking of the lever H', which carries the armature H, is limited by similar adjustable stops H^X. The armature H is also never allowed to come into absolute contact with the 70 cores E of the electromagnets. Preferably also its face is covered with paper or like material, so that the magnetic circuit of the electromagnet is never absolutely complete through good magnetic conducting metal, and therefore the fact of the armature H being held up to the magnet-cores E does not prevent the polarity of these cores being varied when alternate currents are passed through the magnet-coils, and consequently does not prevent 80 the polarity of the arms E', which extend from the cores or pole-pieces, being in this way varied at each reversal of current, so that they may serve to rock the armature G.

Two type-wheels C^X are, as shown, carried 85 side by side on the type-wheel axis C. These can be pressed endwise along the axis by a coiled spring C', but cannot turn around it.

K is a small metallic slide which passes through a slot formed transversely through 90 the axis C. On the slide is a V-shaped projection K'. The boss C², which carries the type-wheels, carries at its end a small roller C³, which by the action of the coiled spring C' is always kept bearing against one or other inclined side of the V projection. When it bears against one incline, one type-wheel is in position for printing, and when it bears against the other the other type-wheel is in position for printing. The two positions are shown 100 in Figs. 4 and 5. A pin K² restrains the slide from being moved too far in one direction. A link K³, which is jointed to the axis C and to the slide, restrains the slide from being shifted 105 too far in the opposite direction.

Whenever the rotation of the type-wheel axis C is arrested at the time when one or other end of the slide K is opposite to the projection L on the printing-lever and the printing-lever is lifted in the manner above 110 described, the projection comes against the end of the slide and moves the slide endwise, so causing the type-wheels to be shifted endwise along the shaft, whereby the type-wheel which before was in acting position is put 115 out of action and the other takes its place.

What I claim is—

1. In a step-by-step printing-telegraph instrument, the combination of the electromagnet, the side extensions from its two pole-pieces in planes at a distance apart from one another, the intermittently-driven printing-axis, its escapement, the armature operating said escapement carried opposite the ends of the pole-pieces, the type-wheel, its intermittently-driven axis, its controlling-escapement, the armature operating said escapement and mounted centrally on an axis with its ends respectively opposite the ends of the side extensions from the pole-pieces of the magnet 125 and having its magnetic continuity interrupted at or about midway of its length, the 130

permanent magnet magnetizing the pole-pieces to one polarity and the ends of the last-named armature to the opposite polarity, and means actuated on the operation of the printing-axis to take an impression from the type-wheel.

2. In a step-by-step printing-telegraph the combination of the type-wheel axis, the cross-slide carried by it, the two type-wheels, the spring holding these wheels up to the cross-slide, the printing-lever by which the cross-slide can be struck and shifted endwise whenever the printing-lever is operated at a time when one or other end of the slide is opposite to it and the inclined projection on the cross-slide by which whenever the slide is shifted endwise one type-wheel is shifted into and the other out of acting position and the wheels retained in whichever position they are moved into.

3. In a step-by-step printing-telegraph instrument, the combination of the intermittently-driven type-wheel axis, the intermittently-driven printing-axis, the two escape-
ments controlling the turning of these axes, the electromagnet having side extensions from its pole-pieces, an armature mounted opposite the pole-pieces of the electromagnet

and operating the printing-axis escapement, the armature operating the type-wheel-axis escapement and mounted centrally on an axis with its ends respectively opposite the ends of the side extensions from said pole-pieces and having its magnetic continuity interrupted at or about midway of its length, the permanent magnet magnetizing the pole-pieces to one polarity and the ends of the last-named magnet to the opposite polarity, the cam on the printing-axis, the printing-lever which it operates, the cross-slide carried by the type-wheel axis in such a position that it may be struck by the printing-lever and shifted endwise whenever the printing-lever is operated at a time when one or other end of the slide is opposite to it, the two type-wheels, the spring pressing these two wheels toward the slide and the inclined projection on the slide which when the slide is shifted endwise shifts one type-wheel into and the other out of acting position and retains them in whichever position they are moved into.

WALTER SAMUEL STELJES.
